UNITED STATES PATENT OFFICE.

ROBERT EDWARDS, OF MARTINS FERRY, OHIO.

MECHANISM FOR OPENING SHEETS.

1,372,018.

Specification of Letters Patent. Patented Mar. 22, 1921.

Application filed December 8, 1919. Serial No. 343,416.

To all whom it may concern:

Be it known that I, ROBERT EDWARDS, residing at Martins Ferry, in the county of Belmont and State of Ohio, a citizen of the United States, have invented or discovered certain new and useful Improvements in Mechanism for Opening Sheets, of which improvements the following is a specification.

10 In the manufacture of sheets, it is the practice to reduce the sheet bars to a certain thickness or gage, then place two of such relatively thick sheets together and roll this pair to a smaller gage and then to form 15 a pack by doubling the pair of sheets on themselves repeatedly, each doubling followed by a rolling operation until the desired gage is obtained.

In opening these packs, *i. e.*, separating 20 the sheets, one from the other, some sheets will stick very tightly, and in such cases, it is the present practice for the opener to place the sheets on the floor and put his foot on the lowermost sheet, seize the upper- 25 most sheet with tongs and pull it loose. This operation is laborious and difficult and consumes considerable time.

The object of the invention described herein is to provide mechanically operated 30 means adapted to grip the respective sheets and pull them in diverging directions. The invention is hereinafter more fully described and claimed.

In the accompanying drawings forming a 35 part of this specification, Figure 1 is a sectional elevation of my improved sheet separating mechanism and Fig. 2 is a sectional plan view, the plane of section being indicated by the line II-II, Fig. 1.

40 In the practice of the invention two rolls, 1 and 2, are mounted in suitable bearings 3 and 4 arranged in the housing 5, the bearing of the upper roll being adjustable. Intermediate the bearings of these rolls are 45 formed recesses 6 adapted to serve as guides for the blocks 7 which are provided with suitable bearings for the journals of small rolls 8. The bearings for these blocks and the arrangement of the rolls 8 in the blocks 50 are such that by shifting the blocks inwardly, sheets fed in between the rolls 8 and the rolls 1 and 2 will be frictionally engaged by the surfaces of the rolls. The blocks 7 are provided with stems 9 extending 55 backward through the housing and suitable means are provided whereby pressure may

be exerted on these stems to shift the blocks 7 and the rolls carried thereby, so that the latter will be caused to bear upon the sheets which are then gripped by driving rolls 1 60 and 2 and the rolls 8. A suitable construction for thus shifting the blocks 7 consists of central heads 10 and oppositely arranged struts 11 having their inner ends bearing on opposite sides of their heads and the outer 65 end of one pair of the struts bearing against the stems 9 while the outer end of the other struts will bear against adjustable abutments 13. These heads are provided with stems 14 extending downward and connected to arms 70 15 on a shaft 16 which can be rotated to pull down the heads by a treadle 17. In order to move the blocks and the rolls 8 away from the driving rolls, springs 18 are interposed between these blocks and opposed faces 75 of the housing, as shown in Fig. 2, the springs being preferably arranged around rods 19 having one end connected to the blocks and the other end movable in openings in the housing. In order to guide the sheets 80 into the bites between the rolls 8 and the driving rolls, a wedge block 20 is arranged in front of the rolls as clearly shown in Fig. 1.

In operating this mechanism to open 85 sheets, the opener will partially open the sheets and then press them against the wedge which will guide the respective sheets into the bite between the driving rolls and the rolls 8, then the operator places his foot upon 90 the treadle pushing the rolls 8 toward the driving rolls and thereby gripping the respective sheets which are then drawn between the respective pairs of rolls.

I claim herein as my invention:

1. In a machine for opening sheets, the combination of two driven rolls spaced a distance apart, two rolls arranged on the same side of a vertical plane passing through the axes of the driven rolls, movable in the 100 space between the driven rolls, and means for moving the intermediate rolls toward the respective driven rolls.

2. In a machine for opening sheets, the combination of a housing, two rolls mounted 105 in suitably spaced bearings in said housing, means for driving said rolls, blocks movable in the housing intermediate the bearings for the driven rolls, rolls mounted in said blocks and means for shifting said blocks in 110 the same direction toward a plane passing through the axes of the driven rolls and

thereby bring the rolls carried by the block into operative relation to the respective driven rolls.

3. In a machine for spacing sheets, the combination of a housing, two rolls mounted in suitably spaced bearings in said housing, means for driving said rolls, blocks movable in the housing intermediate the bearings for the driven rolls, rolls mounted in said blocks,

means for shifting said blocks toward a plane passing through the axes of the driven rolls and thereby bring the rolls carried by the block into operative relation to the respective driven rolls and a V-shaped block arranged on the feed side of the rolls. 15

In testimony whereof, I have hereunto set my hand.

ROBERT EDWARDS.
